No. 6,829

Feb. 20, 1872.

UNITED STATES PATENT OFFICE.

WILLIAM McCALLUM, OF YONKERS, ASSIGNOR TO JOSEPH WILD & CO., OF NEW YORK, N. Y.

DESIGN FOR A CARPET-PATTERN.

Specification forming part of Design No. 5,549, dated February 20, 1872.

Specification describing a new and original Design for Carpet, invented by WILLIAM McCALLUM, of Yonkers, in the county of Westchester and State of New York.

The accompanying photographic illustration fully represents my new design for a carpet.

The same consists, first, of a new central figure, A, which contains in the middle a quatre-foiled field, *a*, surrounded by a square, *b*, which is within a curvilinear quadrangle, *d*, as shown. The invention also consists in the new design for the figure marked B, which at the ends has goblet-shaped excrescences *ee*; and thirdly, in the design for the scroll-work C that fills the space between the figures A

and B, and which is fully depicted in the photograph. Finally, the invention consists in the combination of all the parts above enumerated.

I claim as my invention—

1. The design for the central figure A, as described.
2. The design of the figure B, as shown.
3. The design of the scroll-work C, as shown.
4. The design for a carpet containing the several parts A, B, and C, as shown.

WILLIAM McCALLUM.
